PERMUTATION ELECTRIC SWITCH

William Leonard Tate, Liverpool, and Arthur
Aloysius Oakes, Nottingham, EnglandApplication November 26, 1947, Serial No. 788,246
In Great Britain March 20, 1946

9 Claims. (Cl. 200—43)

1

This invention relates to a permutation electric switch which, while suitable for controlling electric circuits generally, is particularly applicable for controlling the ignition circuit on a motor car or like motor road vehicle.

An object of the invention is to provide for the said purpose an improved permutation switch of the kind comprising a movable member and a plurality of rods operable, against resilient means such as springs, by means of push buttons which are identified by associated numerals, letters or other symbols, a selected plurality of said rods being adapted when actuated in predetermined sequence to effect progressive movement of a member which at the end of such movement closes the electric circuit.

According to the invention, the improved permutation switch comprises a movable member, such as a plate, disc or the like, having a series of slots therein, a plurality of push-button operated rods each slidably traversing one of said slots and thereby limiting movement in opposite directions of said member, switch means associated with the movable member disposed to close the electric circuit by displacement of the member to one operative limit of its movement and to open said circuit by return of the member towards its opposite inoperative limit, a selected plurality of the rods being adapted when operated in predetermined sequence to displace the member progressively to said operative limit, and the remainder of the rods being each adapted to return the member to its inoperative limit.

In the accompanying explanatory drawings a permutation switch is illustrated suitable for use on a motor car.

Fig. 1 being an elevation,

Fig. 2 a plan and

Fig. 3 a linear developed elevation of the circular row of push buttons for operating the switch.

Fig. 4a is a plan of the rotatable plate in the switch and

Fig. 4 is a section on the line 4—4, Fig. 1.

Fig. 5 is a fragmentary view showing the position of the switch arm when the ignition circuit is open and the indicator or pilot light glowing,

Fig. 6 being a similar fragmentary view showing the position of the switch arm closing the ignition circuit.

Fig. 7 is a fragmentary elevation of one push button providing a warning signal for closing the horn circuit of the car,

Fig. 8 being a side view of Fig. 7.

Fig. 9 is a view similar to Fig. 7 showing the

2

push button depressed and retained in position closing the horn circuit.

Fig. 10 is a fragmentary elevation partly in section, and

Fig. 11 an inverted plan of a switch control for the indicator pilot light.

Fig. 12 is a fragmentary elevation and

Fig. 13 a plan of the horn circuit-closing switch actuated by lifting the engine bonnet of the car.

10 A permutation switch applicable for controlling the ignition circuit of a motor car is illustrated in the accompanying drawings, and comprises a framed casing consisting of three plates 1, 2, 3 spaced apart and connected by posts 4, the upper and lower plates 1 and 3 being preferably of fibre or some insulating material. The framed casing is set in an aperture in, say, the dashboard 5 of the car, and mounted to slide transversely in the three plates 1, 2, 3 are a number of push buttons

15 6 under spring controls 7, and each having a collar 7a urged by the spring against the underface of the upper plate 1. Rotatably mounted on a pivot 8 in the casing is a disc 9, having therein a number of separated slots 10 circularly arranged, Fig. 4a. The rods of the push buttons 6 slide in the slots 10 when the buttons are depressed and the parts 11 of the rods engaging the slots are of square section, Fig. 4, so that they

20 cannot rotate in the slots, and each rod is provided with a wedge or like shaped fin 12 or 13, the inclined side of which is adapted when depressed to engage any edge of the slot which it overhangs and so impart to the disc 9 a certain angular movement.

25 35 The rods are in two groups, the fins 12 of one group—which may be termed the effective group—pointing in one direction round the disc 9 and the fins 13 of the other or ineffective group pointing in the reverse direction, so that while operation of any rod of the 13 group imparts clockwise movement to the disc 9, any rod of the 12 group imparts anti-clockwise movement. The push buttons 6 by which the rods are actuated carry various indicating numbers as shown, and/or letters,

40 45 and by pressing the effective buttons consecutively in a known code sequence the disc 9 will be rotated by the fins 12 step by step and uni-directionally to an operative limiting position to actuate a switch closing the ignition circuit of the car.

50 55 In the example given the effective buttons of the code for closing the switch are those numbered 9, 4, 1, 7 to be operated in that sequence, and in order that the movable disc 9 cannot be operated by depression of the effective push but-

tons in other than the correct sequence their wedge shaped fins 12, except the fin on the rod of the button numbered 9 which is to be operated first in the correct code sequence, all have a step 14 at the fin base which prevents their being depressed until the wedge fin of the rod to be previously operated in the correct sequence has been already operated. With this object the fin 12 of the rod of the button numbered 9 to be first operated in the code sequence terminates gradually into its rod, the maximum projection of the oblique edge 15 corresponding to the extent of the base step 14 of the fin 12 on the second rod button numbered 4 of the code sequence, the maximum projection of the oblique edge 15 of such second fin determining the extent of the base step 14 on the third rod button numbered 1 of the code sequence, and so on, so that prior depression of the second or third buttons in the code is prevented by the base steps of the fins overhanging the operative edge beneath of the slot in the movable disc 9, until such edge has first been moved clear of the base step by rotation of the disc 9 by a rod previously operated in correct sequence.

In this way if the effective push buttons be depressed in other than the correct code sequence the plate cannot be rotated. The fins 13 of the ineffective buttons engage the left hand edges, Fig. 3, of the slots 18 in which they slide while the effective buttons engage the right hand edges of their slots and the projecting extent of every fin 13 in the ineffective group is such that when depressed they each move the rotatable plate angularly to the same extent and not step by step as do the effective buttons. Consequently if the device be operated without knowing the correct code sequence any chance sequential operation of certain of the effective buttons moving the disc 9 in the switch closing direction will be neutralized by operation of any one button of the ineffective group, the disc being rotated in a contrary direction to its inoperative limiting position.

The correct and complete operation of the disc 9 by the known code sequence of buttons moves the disc, as indicated by the arrow, Fig. 6, to a position such that a roller 40 or other contact on the disc engages the T-head 16 of a rocking arm 17 pivoted at 18 on the lower plate 3 and throws over the arm to engage one contact 42 of a switch and close the ignition circuit *a* of the car. If, however, any one of the ineffective push buttons be operated, the disc 9 will be rotated in the opposite direction indicated by the arrow, Fig. 5, the roller 43 throwing over the arm 17 to the other switch contact 49 opening the ignition circuit and closing the circuit *b* of a pilot or indicator light 20 at some convenient position on the dashboard.

The pilot 20 is thus normally on when the ignition circuit is open, but out when the switch is closed. The rocking arm 17 of the switch is spring-controlled so that it tends normally to move to the position Fig. 5 interrupting the ignition circuit and closing the pilot light circuit. When, therefore, the effective buttons of the code have been correctly depressed in sequence, the pilot light 20 will be cut out, the extinguishing of which thus denotes that the ignition circuit is closed, so that if the mechanism be in correct working order it is impossible for the ignition circuit to be closed and the pilot light to be on at the same time.

The contact head 16 of the switch arm 17 may

be curved or recessed for engagement by the roller 40 to obtain a more effective closing and opening action of the switch.

Certain of the button rods in the effective group 5 carry contacts which, when such rods are depressed, engage other contacts, thus closing the circuit of the electric horn of the car to give an audible alarm that the device is being tampered with.

Such an arrangement is illustrated in Figs. 7 to 9 where the sliding rod 11 of one of the push buttons 6 carries a bent spring contact 21 adapted to engage a contact 22 carried on an insulating arm 23 on the rotatable disc 9. Normally the 15 relative positions of the two contacts would be as shown in Fig. 7 but if the button 6 be depressed the contact 21 ultimately clicks beneath the contact 22 to close the circuit *c* of the horn 24, Fig. 8. The hooked formation of the contact-carrying arm 23 retains the contact 21 in engagement as the rod rises under its spring control 7, so that the horn will continue to sound until the disc 9 is rotated by pressure of certain buttons of the code sequence carrying the contact 22 sideways and moving it clear of contact 21 and opening the horn circuit.

The circuit of the pilot light 20 being normally closed when the ignition circuit is open, in order to avoid continuous illumination of the light at 30 times other than when required an additional control switch may be provided, Figs. 10 and 11, consisting of a tubular member 25 in which the pilot light 26 is housed and which is rotatable in the fibre or other insulating plate 1 of the device, the tubular housing having a projecting switch arm 26 movable into engagement with a fixed terminal contact 27 when the light is required, but by turning the member 25 the contacts are separated to open the circuit.

With a view to preventing unauthorised short-circuiting of the ignition switch by unauthorised lifting of the car bonnet or tampering with any other movable part of the vehicle and connecting the circuit wires to enable the car to be driven away a device shown in Figs. 12 and 13 may be provided. This consists of a contact 28 sliding in an insulating block 29 and urged by a spring 30, one wire of the horn circuit *c* being connected to this sliding contact. Another fixed contact 31 insulated in a block 32 is connected to the other wire of the horn circuit. Normally the contacts 28, 31 are separated as shown and the horn circuit interrupted by an insulating member 33 carried on the lower edge of a side wing 34 of the engine bonnet. If the bonnet be lifted unauthorisedly the contact 28 will make contact with the contact 31 to close the circuit *c* and sound the horn. Means may be provided for rendering the horn circuit closing action of the contacts 28, 31 inoperative, when desired, and such means may be operated by depressing certain of the effective buttons 6 of the device.

Other circuit closing buttons may be provided in the casing if desired, one 43, Fig. 2, for the side 65 lights and another 44 for the headlights.

Any desired variation of the code number or lettering may be obtained by changing the position of the push buttons and rods and in this way the tamper-proof effectiveness of the device 70 rendered very secure.

What we claim is:

1. A permutation switch for controlling an electric circuit, comprising a movable switch-actuating member having a series of slots therein, a plurality of push-button operated rods each

slidably traversing one of said slots and thereby limiting movement in opposite directions of said member, switch means operable to close the electric circuit by said member on its displacement to the one operative limit of its movement and to open the circuit by the member returning towards its opposite, inoperative limit, a selected plurality of the rods having each one of a series of progressively larger wedge-shaped fins extending towards said operative limit and engageable in the slots to effect successively greater step-wise displacements of the member to said operative limit, and the remainder of the rods having each a wedge-shaped fin extending towards said inoperative limit and engageable in one of the slots to effect displacement of the member towards its inoperative limit.

2. A permutation switch for controlling an electric circuit as claimed in claim 1, in which each of the progressively larger fins has at its base and bearing on the movable member a step which corresponds in extent to the maximum projection of the fin on the rod having prior operation in the permutation sequence, such base step preventing operation of any of said selected rods out of its predetermined sequence by overhanging the edge of the slot in which its rod slides until such edge is moved clear of the base step upon displacement of the member by operation of the rod previously actuatable in the sequence.

3. A permutation switch for controlling an electric circuit as claimed in claim 1, said switch means being a two-throw switch operable to close an engine ignition circuit by displacement of the movable member to its operative limit, and alternatively operable by displacement of said member from said limit to energise a pilot light indicating that the ignition switch is open.

4. A permutation switch for controlling an electric circuit as claimed in claim 1, including an electric contact on at least one of the rods and another contact on the movable member, said contacts being mutually engageable in self-retaining circuit-closing connection by operation of said rod and disengageable by displacement of said member under operation of one of said selected plurality of rods.

5. A permutation switch for controlling an electric circuit, comprising a turnable switch-actuating disc having a circular series of slots therein, a plurality of push-button operated rods each slidably traversing one of said slots and thereby limiting movement in both directions of the disc, switch means operable to close the electric circuit by said disc turning to the one operative limit of its movement and to open the circuit by the disc returning towards its opposite, inoperative limit, a selected plurality of the rods having each one of a series of progressively larger wedge-shaped fins extending towards said operative limit and engageable in the slots to effect successively greater step-wise displacements of the disc to said operative limit, and the remainder of the rods having each a wedge-shaped fin extending towards said inoper-

ative limit and engageable in one of the slots to effect displacement of the disc to said inoperative limit.

5 6. A permutation switch for controlling an electric circuit as claimed in claim 5, including an electric contact on at least one of the rods and another contact on the turnable disc, said contacts being mutually engageable in self-retaining circuit-closing connection by operation of said rod and disengageable by turning of said disc under operation of one of said selected plurality of rods.

10 15 7. A permutation switch for controlling an electric circuit, of the kind comprising a movable switch-actuating member, a plurality of push-button operated rods, means on said rods engageable with abutments on said member under sequential operation of the rods to effect successively greater displacements of the member to an operative limit, and switch means operable by the member at said limit to close the electric circuit, having in combination a further plurality of like rods and in association with each of said rods a projection engageable under 20 25 operation of the rod with one of the abutments on the member to effect positive displacement of the movable member from its switch-actuating limit.

30 35 8. A permutation switch for controlling an electric circuit, of the kind comprising a turnable switch-actuating disc, a plurality of push-button operated rods, means on said rods engageable with abutments on said disc under sequential operation of the rods to effect successively greater angular displacements of the disc to an operative limit, and switch means operable by the disc at said limit to close the electric circuit, having in combination a further plurality of like rods and in association with each 40 45 50 of said further rods a projection engageable under operation of the rod with one of the abutments on the disc to effect positive displacement of the disc from its switch-actuating limit.

9. A permutation switch for controlling an electric circuit as claimed in claim 8, wherein said abutments on the disc are a circular series of slots each traversed by one of the rods, and each of said projections on said further plurality of rods is a triangular fin engageable cam-wise with an end of the slot traversed by its associated rod.
